T. ELLIOTT,
STEEL CAR CONSTRUCTION,
APPLICATION FILED APR. 9, 1919.

Patented Apr. 26, 1921.

2 SHEETS—SHEET 1.

INVENTOR
Thomas Elliott,
BY
Danieline Goulein,
ATTORNEYS

UNITED STATES PATENT OFFICE.

THOMAS ELLIOTT, OF CINCINNATI, OHIO, ASSIGNOR TO THE CINCINNATI CAR COMPANY, OF CINCINNATI, OHIO, A CORPORATION OF OHIO.

STEEL CAR CONSTRUCTION.

1,375,787.

Specification of Letters Patent. Patented Apr. 26, 1921.

Original application filed March 13, 1919, Serial No. 282,338. Divided and this application filed April 9, 1919. Serial No. 288,617.

To all whom it may concern:

Be it known that I, THOMAS ELLIOTT, a citizen of the United States, residing at Cincinnati, in the county of Hamilton and State of Ohio, have invented certain new and useful Improvements in Steel Car Constructions, of which the following is a specification, reference being had therein to the accompanying drawing.

10 This invention relates to improvements in steel car construction and is a division of the subject matter contained in my copending application, Ser. No. 282,338, filed March 13, 1919.

15 The particular object of the present invention is to provide an integral belt rail adapted to be used in connection with a car construction of the character disclosed in the application for Letters Patent referred 20 to, or any other suitable construction in connection with which devices of this character are used.

A further object of the invention is to provide an integral belt rail shaped to extend longitudinally of the car body and to be inclined inwardly and upwardly to intersect the side posts of the car frame and to serve as a sill for the lower sash and a weather strip and flashing beneath the sash 30 rail; a portion of the rail extending downwardly over the upper edge of the girder plate and acting as a reinforcement therefor.

An important advantage of the improved 35 belt rail consists in its peculiar shape and integral construction whereby flashings and calking of joints are eliminated. This is of importance in car building as it materially cheapens this detail of construction, but it 40 is of greater importance in car maintenance as all possibility of spreading and leaking joints is overcome, thus resulting at all times in air and water tight construction which effectually prevents ingress of air, dust or 45 moisture to the interior of the car, without the usual trouble and cost incident to maintenance.

In the accompanying drawings;

Figure 1 represents the side of a car 50 equipped with my improved belt rail.

Fig. 2 represents an enlarged view with the parts partly broken away to show their internal relations.

Fig. 3 represents a longitudinal section in elevation of my improved belt rail showing 55 the arrangement of the rivet holes for securing the rail to the girder plates and side posts of the car;

Fig. 4 is a transverse cross sectional view showing the curvature of the different 60 portions of the rail;

Fig. 5 is a detailed sectional view showing the rail assembled on the girder plate and side posts, and the manner in which the lower sash rail and inner window sill are 65 related thereto;

The lower portion 1 of the belt rail, as here shown, consists of a substantially vertical, longitudinal section extending around the car except over spaces occupied by entrance and exit doors. An inclined portion 70 2 and a substantially vertical portion 3 extend coextensively longitudinally with the portion 1; the part 2 being inclined inwardly and upwardly at a suitable angle to 75 serve as a sill for the lower sash, and the part 3 acting as a weather strip for the lower sash rail 4 and the inner sill casing 5. The longitudinal portion 1 is provided with rivet holes 6 spaced apart to secure 80 the belt rail to the girder plate 7 and the side posts 8; the rail as a whole acting as a lateral brace to the side posts and as a reinforcing plate for the girder plate.

As shown in Figs. 2 and 5 of the drawings, 85 the upper portions 2 and 3 of the belt rail are adapted to intersect the side posts 8, a portion of the posts being cut away to provide clearance for the rail, as shown.

As shown in Figs. 2 and 5 the integral 90 construction of the belt rail eliminates the joints and seams incident to a separate flashing and weather strip and makes a neat, compact juncture between the girder plate 7 and the lower sash, resulting as a whole in 95 a construction of great strength which will remain normal under all conditions of use.

The belt rails may be of any weight and strength desired to suit different types and different weight cars. The rails serving as 100 reinforcing for the girder plate, the plates may be of lighter gage than are used in common practice, thus effecting economy in cost of construction and resulting in a material decrease in the total weight of the car. 105

Having thus fully described my invention,

what I claim as new and desire to secure by Letters Patent, is:—

1. In a belt rail consisting of an integral plate having a substantially vertical, longitudinal portion adapted to be secured to the side posts and girder plate of a car, an upwardly and inwardly inclined portion serving as a sill for the lower sash of said car, and a substantially vertical, upwardly extending portion serving as a weather strip for the lower rail of said sash, said portions extending in single lengths between the doors of the car and having their longitudinal edges substantially parallel to each other.
2. In a belt rail consisting of an integral plate having a substantially vertical portion extending in unbroken sections between the doors around the car and adapted to be secured to the girder plates and side posts thereof, an upwardly and inwardly inclined portion serving as a sill for the lower sash of said car, and a substantially vertical, upwardly extending portion serving as a weather strip for the lower rail of said sash.
3. In a belt rail consisting of an integral plate having a substantially vertical, longitudinal portion adapted to be secured to the side posts of a car, an upwardly and inwardly inclined portion serving as a sill for the lower sash of said car, and a substantially vertical, upwardly extending portion serving as a weather strip for the lower rail of said sash, said portions extending in single lengths between the doors of the car and having their longitudinal edges substantially parallel to each other.
4. In a belt rail consisting of an integral plate having a substantially vertical, longitudinal portion adapted to be secured to the girder plate of a car, an upwardly and inwardly inclined portion serving as a sill for the lower sash of said car, and a substantially vertical, upwardly extending portion serving as a weather strip for the lower rail of said sash, said portions extending in single lengths between the doors of the car and having their longitudinal edges substantially parallel to each other.
5. In a belt rail consisting of an integral plate having a substantially vertical longitudinal portion adapted to be secured to the side posts and girder plate of a car, an upwardly and inwardly inclined portion serving as a sill and an upwardly extending portion serving as a weather strip for the lower sash of said car, said portions extending around the car coextensively with said longitudinal portion, and having their longitudinal edges substantially parallel to each other.
6. In a belt rail consisting of an integral plate having a substantially vertical, longitudinal portion adapted to be secured to the side posts and girder plate of a car, an upwardly and inwardly inclined portion serving as a sill for the lower sash of said car, said portions extending in single lengths between the doors of the car and having their longitudinal edges substantially parallel to each other.
7. In a car structure, a belt rail consisting of an integral plate having a substantially vertical portion extending in unbroken sections between the car doors around the car and adapted to be secured to the girder plates and side posts thereof, said rail having an upwardly and inwardly inclined portion serving as a sill for the lower sash of the car and a substantially vertical upwardly extending portion serving as a weather strip for the lower rail of the sash.
8. In a belt rail consisting of an integral plate having a substantially vertical, longitudinal portion adapted to be secured to the side posts and girder plate of a car, a portion extending upwardly and inwardly from the longitudinal portion at a suitable angle to act as a water shed and sill for the lower sash of said car and extending around the car coextensively with the longitudinal portion and having their longitudinal edges substantially parallel to each other.
9. In a belt rail consisting of an integral plate having a substantially vertical, longitudinal portion adapted to be secured to the side posts and girder plate of a car, a portion extending inwardly from the longitudinal portion and shaped to form a water shed and sill for the lower sash of said car and extending around the car coextensively with the longitudinal portion and having their longitudinal edges substantially parallel to each other.
10. In a belt rail consisting of an integral plate having a substantially vertical, longitudinal portion adapted to be secured to the side posts and girder plate of a car, an upwardly and inwardly inclined portion serving as a sill and an upwardly extending portion serving as a weather strip for the lower sash of said car said portions extending in single lengths between the doors of the car and having their longitudinal edges substantially parallel to each other.
11. In a belt rail consisting of an integral plate having a substantially vertical, longitudinal portion adapted to be secured to the side posts and girder plate of a car, an intermediate inclined portion and a substantially vertical portion extending upwardly therefrom and adapted to serve as a weather strip for the lower sash of said car, said portions extending in single lengths between the doors of the car and having their longitudinal edges substantially parallel to each other.
12. A belt rail adapted to be secured to the side posts and girder plate of a car, an inwardly projecting portion serving as a sill and an upwardly extending portion serving as a weather strip for the lower sash of said car, said portions extending around the car coextensively with said longitudinal portion and having their longitudinal edges substantially parallel to each other.

the girder plate and side posts of a car, and having an integral portion intersecting said posts and serving as a sill and weather strip for the lower sash of said car.

5 13. A belt rail having a portion adapted to be secured to the girder plate of a car to act as a flashing for said plate and having an integral portion intersecting said posts and serving as a sill and weather strip for
10 the lower sash of said car.

14. A belt rail having a portion adapted to be secured to the girder plate of a car to act as a flashing for said plate and having an integral portion intersecting said posts and serving as a sill and weather strip for
15 the lower sash of said car and extending around the car coextensively with the portion secured to the girder plate.

In testimony whereof I affix my signature.
THOMAS ELLIOTT.
